ELECTRICAL DISCHARGE LAMP

Hermann Eduard Krefft, Buenos Aires-Belgrano,
Argentina

Application July 19, 1949, Serial No. 105,526

7 Claims. (Cl. 315—49)

1

The present invention relates to electrical discharge lamps of the high pressure type and more particularly to super high pressure lamps operated under pressures exceeding ten atmospheres which have more than two operating electrodes.

Super high pressure lamps containing mercury vapor, or a mixture of mercury vapor with other vapors, or rare gases under high pressures, are sources of radiation of very high brightness particularly adapted to the uses in projection and searchlights. The manufacture of such lamps, especially for high wattage, however, is extremely difficult as they must be supplied with quartz glass seals and electrodes capable of carrying high currents. The mechanical strength of these seals and of the quartz glass discharge container generally used is not sufficient to allow a safe operation of these lamps the container and seals of which are exposed to high pressures at high temperatures. Moreover, the operation characteristics of these lamps possess many disadvantages mainly connected with the difficulty of starting the arc when the lamp is under pressure.

It is one object of my invention to provide a super high pressure lamp for safe operation. Another object is a lamp with improved operation characteristics. Still another object is a source of light of suitable shape. A further object is a super high pressure lamp of high wattage which can be made with precise dimensions and in large numbers at comparatively low cost. Other objects and advantages of this invention will become apparent from the description hereinafter following and the drawings forming part hereof in which:

Figure 1 is a longitudinal sectional view of a super high pressure lamp constructed in accordance with my invention.

Figure 2 is another sectional view of a lamp according to the invention.

Figure 3 is a transverse sectional view taken on the line 2—2 of Figure 1 illustrating the construction of the seal.

Figure 4 is a diagrammatic section along the line 3—3 of Figure 1 showing the electrode arrangement.

Figure 5 is a schematic representation of a circuit according to the invention.

Figure 6 illustrates a modification of the electrode arrangement for a lamp according to the invention.

Figure 7 is a diagrammatic sectional view taken on the line 4—4 of Figure 6 showing the electrode arrangement.

2

Figure 8 is a schematic representation of another electrode arrangement, and

Figure 9 is a diagrammatic sectional view taken on the line 5—5 of Figure 8 illustrating the electrode arrangement.

According to Figure 1, a lamp embodying my invention comprises a discharge container 1, preferably made of quartz glass, and having a wall thickness of two to three millimeters, provided with short necks 2 and 3 the ends of which are closed by seals 4 and 5, which are, preferably, also made of quartz glass and are firmly welded thereto. Each seal is composed of a plurality of seal elements 6 containing metallic conductors 7 which are electrically connected to the electrodes 8. These electrodes are mechanically supported by discs 9 which are connected to the seals 4 and 5 by means of rods 10 shown in Figure 2. Electrical connection between the seal conductors and the wires or rods 11 carrying the electrodes is made by a series of flexible strips or coils 12 which consist of a metal of high melting point.

The discharge container is filled with a rare gas and a limited quantity of mercury which, under full operation of the lamp, is entirely evaporated and produces a pressure of at least about ten atmospheres. The lamp may also contain limited quantities of other vaporizable metals, or it may contain rare gases only at a pressure exceeding ten atmospheres when the lamp is in operation, or a mixture of such gases at high pressure with metal vapors the pressure of which is not higher than that of the rare gases.

As shown in Figure 2, a lamp according to the invention is also provided with a starting electrode 13 connected to a seal element, e. g. seal element 15, and with a pair of auxiliary electrodes or pilot electrodes 14 and 14'. These pilot electrodes are supported in a similar manner as the main electrodes, and connected to seal elements, e. g. seal elements 16 and 16' respectively. The seals 4 and 5 are also provided with exhaust tubes 17.

The discharge container 1 is a spherical or cylindrical body of uniform wall thickness which is preferably blown in a mold, and advantageously consists of quartz glass. As this material attains maximum mechanical strength at temperatures around 800° C., which is also the operating temperature of the bulb, and since its wall contains no elements like exhaust tubes or seals, it has a considerable mechanical strength sufficient to withstand internal pressures three to four times the operation pressure of the lamp. The

short necks 2 and 3 which form part of the bulb, are cut precisely at right angles to the main axis of the bulb, and their edges are smoothly ground and possess a profile 18, as indicated in Figure 1, which is essential for a good weld with the seals. Into these neck openings, the molded quartz glass discs 19 of the lamp seals fit precisely, and to this end their edges are also accurately ground and provided with a profile corresponding to the profiles of the necks. The manufacture of these seals which are composed of a plurality of seal elements, and their construction, is described in my co-pending patent application Serial No. 105,525 of even date here-with. The metallic conductors which are fused into the seal elements consist of metallic strips, e. g. molybdenum strips, which, under conditions described in my co-pending application, form a vacuum tight seal with the quartz glass. One type of arrangement of the seal elements 6, 15, and 16 on the seal is illustrated by Figure 3 which also shows the positions of the supporting rods 10, and of the exhaust tube 17.

The electrode arrangement is illustrated by Figure 4 showing one set of main electrodes 8, which supply the main arcs while the lamp is in full normal operation, and one of the pilot electrodes 14, which are used for starting the lamp and to maintain a pilot arc which keeps the lamp warmed up and ready for instant operation of the main arcs. The main electrodes consist of tungsten bodies, made e. g. by coiling tungsten wire of circular or square cross-section, or by sintering pure tungsten powder, previously pressed in the desired shape, at high temperatures. These electrodes may be of the non-activated type, or they may contain a body of activating material which, preferably, consists essentially of thorium oxide. The pilot electrodes are of similar construction, but may be smaller in size, and they are activated by a storage body composed of a mixture of thorium oxide and the oxides of barium, calcium, and strontium. For either electrode, when of the activated electrode type, any other suitable activation material may be used, in the form of oxides or other suitable compounds or in the metallic form. Figure 4 also shows the supporting wire 20 of the starting electrode which is arranged in the space between the main electrodes, as shown in Figure 2.

The electrodes are carried by tungsten wires or rods 11 which are firmly connected to the supporting structures 9. These may consist of refractory or ceramic material sintered at high temperatures, like zirconium oxide, as they are exposed to high temperatures when the lamp is operated. Preferably, the supporting wires 11 are sintered into this material. Depending on the electrode arrangement these supporting structures have the shape of a disc, or a ring, or they may be rectangular in shape. They may consist also of a metal, like sheet of molybdenum or tantalum, and in this case, the electrode supporting wires 11 must be insulated from the conducting material of the supports 9. These elements are firmly connected to the seals 4 and 5 by rods 10, preferably made of quartz glass and forming part of the seals.

Electrical connection between the conductors of the seal elements and the electrodes is produced by strips or coils 12 which are welded to the molybdenum foils of the seals and to the wires carrying the electrodes. These strips or coils consist of metals of high melting point,

like tungsten, molybdenum or tantalum, and their lengths and cross sections are conveniently chosen so that a certain amount of heat is produced by the electrical current conducted to the electrodes, sufficient, if necessary, to heat them to incandescence and to warm up the necks of the lamp, and to accelerate the building up of the required high vapor pressure in the lamp.

During manufacture of the lamp, the seals consisting of the molded quartz glass discs 19, the seal elements 6, 15 and 16, the rods 10, and the exhaust tubes 17, as illustrated by Figure 3, are assembled and welded to form one solid body. Then an electrode supporting structure 9, already provided with supporting wires 11, and electrodes 8 and 14, is fastened on to the rods 10, and finally the connecting strips or coils 12 are welded to the electrode wires and the molybdenum strips of the seal elements. The supporting wire 20 of the starting electrode is fastened in a different way as it is convenient to weld it directly to the conductor of the seal element 15, and thus forms part of this element assembled with the seal. This wire is insulated by a quartz glass tube 21 which is welded to the seal, as a high voltage is applied to the starting electrode 13 when the lamp is started under high pressure conditions. After the electrode structure of the lamp is completely assembled in this way, the seals are welded onto the neck openings of the bulb. In order to produce a good weld, both the discs of the seals and the openings of the necks are previously given precise dimensions by grinding, and in this way the weld can be made in a high temperature electrical furnace and/or by means of a hydrogen-oxygen flame without appreciable deformation of the quartz material. During this process, the electrode structure is protected against oxidation by an inert atmosphere. When both seals have been welded, the lamp, which is preferably provided with two exhaust tubes in order to improve pumping speed and permit continuous flushing with a rare gas during the exhaust process, is degassed by application of heat, bombardment of the electrodes, and running of a discharge, and finally filled with a rare gas and the desired vaporizable metal or metals, and finally sealed off.

As the mechanically weakest part of the lamp container is the seal and the weld between the seals and the necks, these welds must be made very carefully and special care must be taken that no sharp angles are formed or remain internally, which would lower the mechanical strength of this part of the container. A good weld is obtained if, as illustrated in Figure 1, the discs 19 of the seals are given a cup like shape so that after the weld has been made, the inside surface obtains a round and smooth curvature as shown in Figure 2. As the spherical or cylindrical bulb itself has a much higher mechanical strength than this weld and the seal, an accidental explosion of the lamp can only start here. In order to prevent the main body of the container from being affected in such a case, it has been found useful to provide the necks, near the seal weld, with a slight rib or constriction which will stop cracks developing in the weld.

The strips or coils 12 are preferably made of tantalum as an absorbing or gettering material used at an adequate temperature has been found to improve very considerably both starting of the discharge and lamp life.

If the lamp is to be used as a rare gas super high pressure lamp, krypton or xenon are preferably filled into the container at pressures above ten atmospheres. In the case of mercury, or of mercury containing some additions like cadmium, zinc, or thallium, a limited quantity is introduced into the container sufficient to produce vapor pressures above 10 atmospheres, preferably in the range of twenty to thirty atmospheres when under full operation of the lamp all the material, or at least the mercury, is evaporated. Such metal vapor super high pressure lamps usually also contain a small amount of a rare gas for starting the discharge, but it has been found advantageous to fill such metal vapor lamps with rare gases under pressures of several atmospheres as the warming-up time is considerably reduced. The vapor pressure then may be adjusted somewhat lower than the rare gas pressure.

Lamp dimensions, for a given wattage, depend on optical requirements and the electrical characteristics demanded. Furthermore, stability of the arc and good operating characteristics must be considered. Since the general theory of super high pressure lamps, with respect to the mechanical and gas discharge problems involved, is sufficiently known, dimensions can be computed and adapted to practical conditions by experiment. As a general rule, the relation between lamp watts and surface of the bulb should be 30 watts per square centimeter if the lamp is operated without forced cooling. A practical range for the arc length is five to twenty millimeters. If forced cooling with compressed air is used, the surface load may be raised to near 100 watts per square centimeter.

From the viewpoint of lamp operation, the principal problem of super high pressure vapor lamps is starting under high pressure, and when starting a cold lamp, the production of a high pressure atmosphere within a sufficiently short time.

According to my invention, this problem is solved in the lamp construction already described by providing the lamp with a pair of special electrodes or pilot electrodes. When starting the lamp, a discharge is produced between these electrodes until sufficient metal vapor has developed. Once this arc exists, the main arcs between the main electrodes can be produced any time without the use of high voltage, as the existence of one arc is sufficient, provided this arc, or pilot arc, is not too far away from the main discharge path. In this way, a super high pressure lamp can be kept ready for quick operation either by warming up through the pilot arc or by maintaining this arc immediately after the main arcs have been interrupted. If the pilot arc is not operated during full operation of the lamp, care must be taken that it is produced prior to the interruption of the main discharge.

In the case of a lamp which is provided with four pairs of main electrodes one of these may be used as pilot electrodes, but the use of a special pair of electrodes has many advantages, as size, position, and activation of these electrodes can be chosen according to their special functions. However, a part of the main arcs may be left operating in such cases where an immediate full operation of the lamp is desired. But initial starting and warming up of the lamp should be done always with the pilot electrodes,

as the main electrodes are not adapted to operation under such conditions.

The starting electrode 13, which is built for high voltage operation, is required in such cases 5 when the pilot discharge has been interrupted accidentally, or for initial starting of lamps containing rare gases under high pressure.

The circuit shown in Figure 5 illustrates schematically the operation of a lamp which has 10 four pairs of main electrodes 8 arranged in two sets, one pair of pilot electrodes 14 and 14', and one starting electrode 13. The electrodes 8 and 14 are connected through ballasts or resistances 22 and 23, and switches 24 and 25, 15 in parallel to a source of voltage 26 supplying single phase alternating or direct current at 110 or 220 volts. The starting electrode 13 may consist of pure tungsten and is connected to the secondary coil of a transformer 27 the primary 20 coil of which is connected to the source of voltage through the switch 28.

The lamp is started by closing only those 25 switches of 24 and 25 which lie in the circuit of the pilot electrodes 14, while the circuits of the main electrodes 8 remain open. If necessary, a high voltage is impressed on the starting electrode by closing the switch 28 for a short time. The discharge produced between the pilot 30 electrodes warms up the lamp and raises the vapor pressure to a value sufficient for the operation of the main arcs, which are started by closing the corresponding switches 24 and 25. The main arcs are thus formed at once as the discharge path of the pilot arc transfers itself 35 to the other electrodes as soon as their circuits are closed. As the lamp is now fully operated the final vapor pressure of more than ten atmospheres is soon produced by total evaporation of the metal. While the main arcs are operating 40 the pilot arc can be switched off and stay so as long as the other arcs exist. The pilot arc, however, must be switched on again before the main arcs are interrupted, if the lamp is to be kept ready for further use. When the 45 pilot arc is maintained alone, the vapor pressure will fall off to a certain extent, but the lamp is kept ready for instant starting, as already described, and full vapor pressure can be obtained again within a very short time.

In metal vapor lamps containing a rare gas 50 at low pressure, the starting electrode and its operation with a high voltage of several thousand volts is required only if all the arcs have been interrupted accidentally, and immediate starting 55 of the hot lamp is required. However, the starting electrode is essential when the lamp contains rare gases under high pressure.

The present invention is not restricted to the one example of a lamp containing four pairs of 60 main electrodes arranged in two sets, and in one plane. Obviously, the number of main electrodes may be larger or smaller, and each set of electrodes can be arranged to form two rows, a triangle, or a square. The lamp can also have but 65 one neck, and in this case all the electrodes would be mounted on one seal, or the bulb is provided with three or four necks and a corresponding number of seals carrying more than two electrode sets. As there are many possibilities 70 for the construction of lamps according to my invention, any desired geometrical combination of arcs can be produced by suitable electrode arrangements. My invention is also not limited to the use of single phase alternating currents.

75 A modification of a lamp according to my in-

vention is shown in Figure 6. The discharge container of this lamp is provided with two seals 4 and 5 of which each carries three pairs of main electrodes 29, 30, 31 and 33, 34, 35 respectively, which are arranged in a triangle, as illustrated by Figure 7. The pilot electrodes 32 and 36, are arranged in the axis of the lamp, and closer to the seals than the main electrodes.

When this lamp is operated with a circuit similar to the one shown in Figure 5, four arcs can be formed between corresponding main electrode pairs and the pilot electrodes. However, if three phase voltage is used for the operation of the lamp a larger number of arcs can be produced. In the case of a three phase four wire system, when the neutral conductor is connected to the pilot electrodes while the phases are connected through ballasts to the main electrodes, phase displaced arcs are produced within each electrode set and the corresponding pilot electrode, and between the two sets also wherever potential differences between electrodes exist. It is often advantageous to use two separate three phase systems which are electrically independent from each other, as in this case the arc between the pilot electrodes can be produced, or arcs within each set and the pilot electrode only, or arcs between the two sets without the other arcs.

The use of pre-heated electrodes as pilot electrodes is illustrated by Figure 8 which shows schematically the electrode arrangement of a super high pressure lamp provided with two pairs of main electrodes 37, 38 and 39, 40 and with one pilot electrodes 41, and 42, which are of the pre-heated type, and therefore possess two leading-in conductors each. The electrode arrangement of this lamp is further illustrated by the transverse view of Figure 9. Starting of this lamp, and the production of a metal vapor atmosphere of sufficient pressure for the operation of the main arcs, is particularly facilitated as the heating of the electrodes will both lower the starting voltage and contribute to the warming up of the necks and seals of the lamp. Under high pressure, however, as already explained, one arc must be maintained always for instant operation of the lamp.

Super high pressure lamps of high wattage have been made up to now with one arc only, and for this reason they had to be supplied with large electrodes and seals of high current capacity both of which are difficult to make and lead to constructions of the discharge container of reduced mechanical strength. They are not adapted to economical and large scale manufacture, and their operating characteristics are little satisfactory, as a heavy electrode is hard to start and cannot be operated reasonably under very different conditions of current and vapor pressure.

What I claim is:

1. A high pressure electrical discharge lamp comprising in combination a glass vessel having an opening, a glass seal member engageable with the walls of said opening to close said opening to form a gaseous discharge envelope, an ionizable gas filling within said envelope, said seal member having secured therethrough a plurality of substantially elongated glass seal elements each containing an electrical conductor leading to the discharge chamber of said envelope, a plurality of pairs of spaced electrodes within said envelope for maintaining a plurality of discharge arcs, each of said electrodes being electrically connected to one of said seal element conductors, at least a

5 pair of said electrodes operable as main electrodes for full operation of said lamp, another pair of said electrodes each being adjacent to one of said main electrodes and of smaller mass than said main electrodes and operable as pilot electrodes to maintain a pilot discharge arc to keep the lamp ignited and ready for instantaneous full operation of said lamp, each pair of arc maintaining main electrodes being electrically and independently connectable in parallel to a source of current, switch means for each of said parallel connections.

2. A high pressure electrical discharge lamp comprising in combination a quartz glass vessel having an opening, a quartz glass seal member engageable with the walls of said opening to close said opening to form a gaseous discharge envelope, an ionizable gas filling within said envelope, said seal member having secured therethrough a plurality of substantially elongated quartz glass seal elements each containing an electrical conductor leading to the discharge chamber of pairs of said envelope, a plurality of spaced electrodes within said envelope for maintaining a plurality of discharge arcs, each of said electrodes being electrically connected to one of said seal element conductors, at least a pair of said electrodes operable as main electrodes for full operation of said lamp, another pair of said electrodes each being adjacent to one of said main electrodes and of smaller mass than said main electrodes and operable as pilot electrodes to maintain a pilot discharge arc to keep the lamp ignited and ready for instantaneous full operation of said lamp, each pair of arc maintaining main electrodes being electrically and independently connectable in parallel to a source of current, switch means for each of said parallel connections.

3. A high pressure electrical discharge lamp comprising in combination a quartz glass vessel having axial openings, a glass seal member for each of said openings and engageable with the walls thereof to close said openings to form a gaseous discharge envelope, an ionizable gas filling within said envelope, said seal member having secured therethrough a plurality of substantially elongated glass seal elements each containing an electrical conductor leading to the discharge chamber of pairs of said envelope, a plurality of spaced electrodes within said envelope for maintaining a plurality of discharge arcs, each of said electrodes being electrically connected to one of said seal element conductors, at least a pair of said electrodes operable as main electrodes for full operation of said lamp, another pair of said electrodes each being adjacent to one of said main electrodes and of smaller mass than said main electrodes and operable as pilot electrodes to maintain a pilot discharge arc to keep the lamp ignited and ready for instantaneous full operation of said lamp, each pair of arc maintaining main electrodes being electrically and independently connectable in parallel to a source of current, switch means for each of said parallel connections.

4. A high pressure electrical discharge lamp according to claim 1, comprising a starting electrode of tungsten wire electrically connected to one of said seal element conductors and positioned in the path of an arc between said main electrodes.

5. A high pressure electrical discharge lamp

according to claim 1, wherein said main electrodes consist of tungsten bodies and said pilot electrodes consist of activated tungsten bodies.

6. A high pressure electrical discharge lamp comprising in combination a quartz glass envelope having a substantially short opened neck, a molded quartz glass seal member in welded engagement with said neck to provide a sealed envelope, an ionizable gas filling within said envelope, said seal element having secured and sealed therethrough a plurality substantially elongated of quartz glass seal elements each containing an electrically conductive metallic strip leading to the discharge chamber of pairs of said envelope, a plurality of spaced electrodes within said envelope for maintaining a plurality of discharge arcs, each of said electrodes being electrically connected to one of said metallic strips of said seal elements, at least a pair of said electrodes operable as main electrodes for full operation of said lamp, another pair of said electrodes each being adjacent to one of said main electrodes and of smaller mass than said main electrodes and operable as pilot electrodes to keep the lamp ignited and ready for instantaneous full operation, each pair of arc maintaining main electrodes being electrically and independently connectable in parallel to a source of current, switch means for each of said parallel connections.

7. A high pressure electrical discharge lamp comprising in combination a quartz glass envelope having substantially short opened axial necks, a molded quartz glass seal member in welded engagement with each of said necks to provide a sealed envelope, an ionizable gas filling within said envelope, said seal member having secured and sealed therethrough a plurality of substantially elongated quartz glass seal elements, each containing axially thereof an electrically conductive metallic strip leading to the

discharge chamber of said envelope, a plurality of pairs of spaced electrodes within said envelope for maintaining a plurality of discharge arcs, each of said electrodes being electrically connected to one of said metallic strips of said seal elements, a pair of said electrodes being solid incandescent activated pilot electrodes arranged in the axis of the envelope with each of said pair of pilot electrodes being substantially close to a seal member and operable to keep the lamp ignited and ready for instantaneous full operation of said lamp, at least another pair of electrodes being main electrodes arranged near the central portion of said envelope, each pair of arc maintaining main electrodes being electrically and independently connectable in parallel to a source of current by means of a switch in each of the said parallel connections.
